UNITED STATES PATENT OFFICE.

FAY TEMPLETON RODGERS, OF MEMPHIS, TENNESSEE.

DOOR-SECURING DEVICE.

1,373,354.

Specification of Letters Patent. Patented Mar. 29, 1921.

Application filed June 11, 1920. Serial No. 388,265.

To all whom it may concern:

Be it known that I, FAY T. RODGERS, a citizen of the United States, residing at Memphis, in the county of Shelby and State 5 of Tennessee, have invented new and useful Improvements in Door-Securing Devices, of which the following is a specification.

This invention relates to door securing devices and more particularly to that type 10 which are employed for securing refrigerator and ice box doors.

The principal object of the invention is to improve upon the structure in use at the present time and to provide a simple and 15 efficient device which will automatically lock or secure the door when the door is closed and which may be conveniently operated.

A further object of the invention is to provide a device of this character with a spring 20 actuated locking lever and a keeper of such character as to automatically throw the locking lever into position whereby a spring for actuating the lever will throw the same behind the shoulder on the keeper as the door 25 is closed, thereby automatically locking the same.

Further objects of the invention will appear as the following description is read in connection with the accompanying drawing, 30 which forms a part of this application, and in which:—

Figure 1 is a front elevation.

Fig. 2 is a plan view.

Fig. 3 is a side elevation.

35 Fig. 4 is a sectional view on the line 4—4 of Fig. 1.

Fig. 5 is a vertical section on the line 5—5 of Fig. 1.

Referring more particularly to the drawing, 1 represents the door jamb of a refrigerator and 2 the door therefor. Secured to the door in any suitable manner is a plate 3 having rising or extending outwardly therefrom a pair of separated or spaced lugs 4 in which is journaled an axle 5 having secured upon one end a beveled gear 6 and upon the opposite end the operating or locking lever 7. The axle 5 carries a pinion or toothed segment 8 which meshes with the 45 rack tooth 9 on the top of the spring casing 10, slidably mounted vertically of the door through or between the lugs 4. The casing 10 is held upon the plate 3 by the pinion 8 and is normally forced in one direction by the spring 11 which has one end abutting one 50 end of the casing and the opposite end abut-

ting a lug 12, raised from the plate 3 and seated inside of the casing.

The outer end of the lever 7 which is keyed upon the shaft 5 is provided with a 60 laterally extending stud 13 upon which is mounted a roller 14 held in position by the head 15. This roller is adapted to engage the keeper as will be more fully explained hereinafter.

Secured to the jamb 1 is the keeper which consists of an attaching plate 15 which has integrally formed thereon a keeper hook 16 whose inner wall is provided with a cam 17 and its outer edge is inclined, as shown 70 at 18. The rib 19 alined with the hook forms with the hook a groove or channel 20 for the passage of the roller.

Journaled in the boss 21 extending laterally from the plate is an operating shaft 75 22 which is squared on one end to receive the operating handle. This operating handle carries an integral beveled toothed segment 24 which meshes with the beveled tooth segment 6 keyed upon the squared end 80 of the shaft 25. The opposite end of the shaft 22 is threaded for a considerable portion of its length so as to permit the handle 25 to be threaded thereon so as to accommodate the lock to thick or thin doors. The 85 threaded end of the shaft is provided with a key-way 26 and the handle 27 is similarly provided so as to receive a locking key whereby the same may be secured to the shaft in any position of its adjustment.

When either of the handles 23 or 27 is depressed the segment 24 meshing with the segment 6 will cause the rotation of the shaft 25. By this it will be seen that the pinion 8 meshing with the rack bar will 95 contract the spring 11 at the same time turning the lever arm 7 so as to carry the roller out of the channel 20. Upon closing the door the roller will engage the incline 18 and said incline will shift the lever, turning the 100 pinion 8 and moving the casing 10 against the tension of the spring. Immediately upon passing the end of the incline the spring will act to throw the roller into the channel 20 and being guided by the cam 17 105 the lever will act to draw the door in tight engagement with the jamb.

What is claimed is:—

1. In a door securer, the combination with a cam hook keeper, a shaft journaled in the 110 door and carrying a lever arranged to engage the keeper, a spring actuated rack

member and means operated by the rack member for throwing the lever into engagement with the keeper.

2. In a door securer, a hooked cam keeper, 5 a spring actuated rack member carried by the door, a lever arranged to engage the keeper, means operating by the rack member for actuating the lever to engage the keeper and means for turning the lever out 10 of engagement with the keeper against the tension of the spring.

3. In a door securer, the combination with 15 a cam hook keeper, a plate carried by the door, a shaft journaled on the plate and carrying a pinion, a spring actuated rack member engaged with the pinion, a lever carried by the shaft and arranged to engage the keeper, a handle shaft journaled in the plate at right angles to the first shaft and 20 carrying handles and operative connecting means between the first and second shafts.

4. In a door securer, the combination with 25 a cam hook keeper, of a plate secured to the door and having legs extending therefrom, a shaft journaled in the lugs and carrying a lever arranged to engage the keeper, means normally acting to rotate the shaft in one direction, a shaft journaled in the plate at right angles to the first-named 30 shaft and carrying handles and means connecting the first and second shafts.

5. A door securer comprising a cam hook member, a plate carried by the door having lugs extending therefrom, a shaft journaled 35 in the lugs and carrying a pinion, a spring

actuated rack casing slidably mounted between the lugs and engaged with the pinion, a handle actuated shaft journaled in the plate at right angles to the first shaft and segmental gears connecting the first and 40 second shafts.

6. In a door securer, the combination with 45 a cam hook keeper having a lever actuated incline, a plate secured upon the door and having lugs extending therefrom, a shaft journaled in the lugs and carrying a keeper engaging lever, a pinion, a casing slidably mounted between said lugs and carrying a rack arranged to engage the shaft, a spring for actuating the casing in a direction to throw 50 the lever into engagement with the keeper, a shaft journaled in the plate at right angles to the first shaft passing through the door, a handle secured to one end of the shaft, a second handle adjustably secured 55 to the opposite end of the shaft and a gear connection between the first and second shafts, said incline arranged to shift the lever automatically against the tension of the spring when the door is closed and said 60 spring adapted to throw the lever into engagement with the cam of the keeper after the incline is passed.

In testimony whereof I affix my signature in presence of two witnesses.

FAY TEMPLETON RODGERS.
